DISPLAY STAND FOR JEWELRY OR THE LIKE

Robert L. Weber, New Caanan, Conn., assignor to The Risdon Manufacturing Company, Naugatuck, Conn., a corporation of Connecticut

Filed Apr. 22, 1965, Ser. No. 84,915

Term of patent 14 years

(Cl. D80—9)

Fig. 1

Fig. 2

Fig. 3

Fig. 4

FIG. 1 is a front elevational view of a display stand for jewelry or the like embodying my new design;

FIG. 2 is a side elevational view thereof;

FIG. 3 is a top plan view thereof; and

FIG. 4 is a rear elevational view thereof.

The broken line representations of jewelry in FIGS. 1 and 3 are for purposes of illustration only.

I claim:

The ornamental design for a display stand for jewelry or the like, substantially as shown and described.
